GAS CHROMATOGRAPH CONSOLE

John P. Salsgiver, West Acton, Mass., assignor to United Technical Corporation, Auburndale, Mass., a corporation of Massachusetts

Filed Aug. 15, 1967, Ser. No. 8,283

Term of patent 14 years

(Cl. D26—14)

FIG. 1.

FIG. 2.

FIG. 3.

FIG. 1 is a perspective view of the gas chromatograph console showing my new design;

FIG. 2 is a front view of the console; and

FIG. 3 is an end view taken from the right hand end of FIG. 2.

The dominant feature of the design does not relate to the graph paper shown in broken lines in FIGS. 1, 2, and 3.

The left hand of the panel is a mirror image of the right hand, as shown in FIG. 3.

I claim:

The ornamental design for a gas chromatograph console, as shown and described.
